UNITED STATES PATENT OFFICE

2,168,123

PIPE OR TUBE BENDING MACHINE

John Henry Hawes, London, England

Application September 8, 1936, Serial No. 99,821
In Great Britain May 12, 1936

8 Claims. (Cl. 153—45)

- This invention relates to tube or pipe bending machines of the kind in which the tube is bent round a grooved radius wheel or former by means of a radial arm or lever which is swung round the former, the arm acting on the tube through a grooved shield bearing on the tube round the outside of the bend, and the invention relates more particularly to formers for use in such machines.
- 10 In the constructions of such machines as hitherto made, the radius wheel or former has been constructed of cast metal or made of solid construction so that when tubes of slightly different external diameters have to be bent a different grooved former to fit the different external diameters of tubes has been required, since the grooved face of the former can only be given such cross-sectional curvature as to support one particular external diameter of tube and if tubes of smaller diameter than those intended to be bent in the former are used the walls of the tube are not adequately supported and distortion or crinkling of the tube results, while, of course, tubes of slightly larger diameter than those for which the former is intended cannot be bent without distorting or flattening the tube to enable it to enter the groove in the former.

The disadvantage of having a rigid former is particularly apparent in the plumbing industry, where tubes are classified according to their internal diameter or bore, but may be of different gauge material according to the pressure they are to withstand or the strength required, resulting in the use of tubes of the same bore but having different thicknesses of wall and consequently slightly different external diameters.

The cast or solid former is also heavy and this is important when the bending machine is required to be portable.

- 40 Also, with the constructions now generally in use and referring more particularly to those shown in my prior U. S. Patents Nos. 1,505,887 and 1,530,261 only a short straight shield can be used between the tube and the radial lever by 45 which the bending force is applied, so that when the tube has to be bent through the major portion of a circle the shield has to be moved round in steps as the tube is bent. In the present construction the shield is mounted upon a slideable 50 support which in turn is carried by the lever, whereby the shield moves with the lever as the same is operated, and thereby the shield contacts with the tube throughout each bending operation of the lever. In this respect the present invention differs from my prior patents, and

the known art in that the shield does not have to be readjusted for each bending operation of the tube. If an attempt is made to avoid this repeated re-positioning of the shield by using a longer shield it is found that, although the bending force may be suitable at the commencement of the bending operation, by the time the radial arm has been moved so that the other end of the shield is between the tube and the radial arm the force applied to the tube is changed to such an extent that distortion of the tube results.

5 The object of the present invention is to avoid these disadvantages and to provide a former which can be used for slightly different external diameters of tube, and a further object is to provide a machine which enables a considerable bend to be produced without readjustment of the shield between the bending arm and the former.

According to the invention a former for use in a bending machine is bent up or pressed out 20 from sheet metal, and has a cross-section consisting of a semi-circular web having two side wings which preferably project to the diameter of the largest tube which can be fitted into the former so that this tube is completely within 25 the side wings so that these projecting portions of the side wings can receive between them the edges of the shield used between the tube and the bending arm.

30 The invention also includes a construction of a bending machine incorporating a sheet metal former and in the machine according to the invention the shield is permanently carried on the bending arm and is made of a comparatively short length and has its rear or trailing end (that is, the back end as the bending arm is swung round the former) made to fit between the wings of the radius wheel or former, while the leading end projects out from the aforesaid wings and is positioned so that it is spaced slightly 35 from the tube and thus avoids scoring the latter. The concave face of the shield is not made of exact circular cross-section but is made very slightly oval in section so that the shield does not contact with the wall of the tube being bent over the whole of its face but only supports the tube at points other than the extreme outermost circumference of the bend made in the tube by the machine.

40 The edges of the shield taper down to very thin knife-like edges so that the shield can be fitted between the wings of the former until its rear end forms, with the grooved face of the former, a complete practically circular support 45 surrounding the tube.

The shield is preferably so positioned on the bending arm, or the arm itself is so bent, that the application of the bending force occurs about 10° to 25° in advance of a radial line through 5 the point of bending of the tube.

The former according to the invention can be used with a shield of ordinary length and section and the bending force applied to the shield by means of a roller carried on the bending arm, 10 in the usual manner.

One construction of machine according to the invention and incorporating a sheet metal former is illustrated in the accompanying drawings in which:

15 Fig. 1 is an elevation of the bending machine.
Fig. 2 is a plan view of Fig. 1.

Fig. 3 is an end view of Fig. 2.

Fig. 4 illustrates a supporting member which can be used with the machine, while

20 Figs. 5 and 6 show a form of bending arm which can be used, in place of that shown on the machine, when an ordinary detachable shield is used.

The machine is provided with a curved former 25 1 which has the cross-section indicated in Fig. 1 and also shown in end view in Fig. 3 and consisting of a semicircular web portion 11 and side wings 2 which are slightly splayed outwardly so that the groove in the former tapers outwardly, 30 this former being preferably constructed from a flat strip which is first bent transversely to the required cross-section (i. e. a semi-circular web and two splayed side wings) and this strip is then bent round into quadrant form to become the curved and grooved former as will be clear 35 from Fig. 2. To provide a support for the former one end of this quadrant merges into a straight tube 3 while the other end of the quadrant is welded to a cross-tube 4 which has its other end welded to the tube 3 at right angles thereto.

Above the former 1, but spaced therefrom, is positioned another former 5 of smaller size radius and suitable for tubes of smaller diameter and this smaller former may be constructed similarly 45 to the large former 1 from a strip bent to have a requisite cross-section and then curved into quadrant form, its ends being welded to the supporting tubes 3 and 4, or the support for this former 5 may be a flat web 6 which may be formed 50 by pressing in one piece with the former and when the web is provided, as in the construction shown, the small former 5 is secured to the larger one by means of extensions or brackets 7 and 8 which are welded to the exterior of tube 3 and 55 the exterior of tube 4 respectively.

Either of the sheet metal formers and their supports may be constructed as units separate 60 from a bending machine so that they can be substituted for other formers, and the supports can be adapted or modified for use with other constructions of bending machine than that illustrated and described.

The cross tube 4 also forms a support for a 65 pivot pin 9 on which is pivoted a bending lever 10, this lever having two arms 11 and 12 which extend above and below the larger former 1 and have holes in their ends through which the pin 9 passes so that the bending lever 10 can be swung about its pivot pin 9 round the 70 former 1 in the usual manner.

Surrounding the upper arm 11 is a slide 13 75 which has a block portion 14 extending between the two arms 11 and 12 and to the end of this slide is attached a vertical bracket 15 to which is attached the shield 16 associated with the

smaller former 5, while to the block 14 is attached the shield 17 which co-operates with the larger former 1.

The concave faces of these shields are not of true semi-circular cross-section but are made 5 slightly oval in cross-section so that the central part or root of the concave face, indicated at 18 on shield 17, does not come into contact with the wall of the tube (which is indicated in chain-dotted outline in Fig. 1) and the tube is thus acted 10 on only by the parts of the grooved faces of the shields near the edges which taper down to knife-like edges 19 as shown so that each shield can fit within the side wings of the former with which it co-acts. Furthermore, the shields 16 15 and 17 are arranged so that only parts of their edges 19 enter the grooves of the formers while the remaining part of each shield projects out from the former in the manner shown and the machine is intended to be used with these projecting parts as the leading parts of the shields 20 during the bending movement, that is, the bending operation is assumed to take place by moving the bending lever 10 in a clockwise direction as viewed in Fig. 2. Each shield is so positioned 25 that, at the commencement of the bending operation the leading edge of the shield is not in contact with the tube. This prevents scoring of the tube at the start of the bend and it is found that, by slight compression and settlement 30 of the tube during the bending operation, the forward edge of the shield comes into contact with the tube.

The two shields 16 and 17 are so positioned in relation to one another that they both enter their 35 respective formers when the slide 13 is pushed along towards the pivot pin 9 and the slide can be held in position by a removable pin 20, which is conveniently attached by a chain 21 to the bending lever 10, and is passed through holes in 40 the arms 11 and 12 and in the slide 13 and block 14 which are in alignment when the shields are correctly positioned between the wings of the formers as shown. The two shields 16 and 17 are also positioned on the slide 13 so that the bending 45 force acts between 10° to 25° but preferably approximately 15° beyond a radial line passing through the bending point, but if desired the bending lever 10 can itself be cranked to the required extent so that the shields are then positioned at right angles to the cranked part of the 50 bending arm.

There is also provided for each former a stop or abutment against which the end of the pipe being bent, or the length of pipe preceding the 55 bending point, can bear while the bending operation is in progress, and these stops are formed by an arm 22 projecting from a ring 23 which surrounds the tube 3 and is secured thereto by a screw 24 which projects through a slot 24' in the 60 ring 23 to enable the arm 22 to adjust itself, while it is always kept in a convenient position for the insertion or release of the tube. The free end of the arm 22 is bent over as shown at 25 in Fig. 3 so that the bent end can fit round the part of the 65 pipe which projects from the larger former 1 while the arm 22 also has secured to it a curved bracket 26 which similarly acts as a stop or support for pipes bent in the smaller former 5.

The projecting part of the tube 3 can be gripped 70 in a vise or secured to any other suitable support and the hollow interior of the tube forms a socket for the member 27, shown in Fig. 4, which has a reduced end 28 which fits within the tube 3, while the other end of this arm is provided with 75

a rubber foot 29. This member 27 can have its reduced end 28 fitted into tube 3 so that it projects in the same direction as that in which the bending lever is shown in Fig. 2 so that the member 27 forms an arm against which the operator can pull whilst bending the pipe by using the machine after the manner of shears, or the foot 29 can be pressed against the ground and the member 21 used as a supporting leg when the tube is bent by swinging the bending lever in a vertical plane. The tube 3 is also provided with a transverse hole 30 in line with the cross tube 4 so that the reduced end 28 of the member 27 can be fitted into the socket so formed, at right angles to the position previously mentioned, as the bending operation proceeds.

In carrying out the bending operation the bending lever 10 is brought into a position at right angles to that shown and the tube is fitted between the side wings of one or other of the formers 1 or 5, the wings of the former being sufficiently springy (owing to the fact that the former is made of sheet or plate metal) to accommodate tubes of slightly different external diameters, and the end of the tube or the part where the bending is to be commenced is supported by the appropriate stop 25 or 26. The slide 13 is moved along the bending lever towards the pivot pin 9 until the shield fits between the wings of the former and the tube is enclosed between the grooved face of the former and the shield which contacts only at its rear end with the tube, and the shield is secured in position by passing the pin 20 through the holes in the arms 11 and 12 of the bending lever and the hole in the block 14 which come into alignment.

The member 27 is then fitted into the tube 3 to give a purchase for the bending operation, and the bending lever 10 is then pulled round so that the shield travels along the surface of the tube with the end of the shield which projects out from between the wings of the former as the leading or advancing end. It is found that with the arrangement and construction of shield as above described it is possible to produce a considerable bend in a pipe or tube without distortion or damage to the tube and, of course, as the shield travels round with the bending lever there is no need to suspend the bending movement at intervals to readjust the position of the shield.

After the bending movement has been started the member 27 can be transferred from its original position in which it forms a continuation of tube 3 to a position in the socket 30 at the side of tube 3 in line with tube 4 so as to enable greater purchase to be obtained.

If desired, the usual separate shield may be used with a former of the kind above described and in this case the slide 13 and the shields 16 and 17 carried by the bending lever itself are dispensed with and the lever is of the form shown in Figs. 5 and 6. In this case the arms 11 and 12 carry pins 31 and 32 on which rotate rollers 33 and 34, one or other of which can bear on the flat face of a shield located in the well known manner between the roller and the pipe which is being bent. The roller 33 is positioned so that it acts on the shield which co-acts with the larger former 1 while the other roller 34 is positioned so that it can bear on the shield used with the smaller former 5.

Although the machine illustrated has two formers of different sizes it will be obvious that the smaller former can be dispensed with, if necessary, so that the machine is only suitable

for bending pipes of about one standard size although, of course, alternative sizes of separate unit formers may be provided for use with the same bending lever and shield by arranging that these other formers with their supports can be substituted by the operator for that already in the machine.

Furthermore, although the formers shown only extend through approximately a quarter of a circle they can obviously be made semi-circular or nearly completely circular to enable semi-circular and circular bends to be produced in a pipe or tube with one sweep of the bending lever.

By making a former of sheet metal, and not as a casting, the wings or flanges can be made so that they spring slightly when the pipe is placed in the groove of the former, thereby producing the top and bottom pressure which is always required in bending pipes, and is particularly necessary when bending the light gauge copper tubes used in modern hot and cold water systems, while, owing to the ability of the sheet metal former to open out slightly, it can accommodate pipes with slightly different external diameters or pipes of a standard bore but made of different gauge metal and consequently different thicknesses of wall. A former of this kind, therefore, makes it unnecessary to use different formers for slightly different sizes and gauges of tube as is necessary when a cast or rigid former is used, and the sheet metal formers are much lighter than the cast formers, which considerably reduces the weight of the whole machine.

Although the former according to the invention has flanges which project to the full diameter of the tube to be bent, this is not essential when bending thick walled tubes or a tube which has a spring inserted in it while it is being bent and the former can therefore be made of semi-circular shape in section (without the fully projecting flanges) when thick walled tubes only have to be bent.

Also by the use of a shield of the construction above described it is found that distortion or damage to the tube is avoided and an operator can produce any required degree of bend up to the limit of the former without it being necessary to adjust the guide while the bending operation is in progress.

A machine of the construction shown can also be quickly clamped in a vice or can be used apart from any rigid foundation on which to secure the former as the bending lever can be swung round towards the arm 27 (when fitted into the tube 3) in a similar manner to the use of a pair of shears, or, of course, this member 27 can be pressed against the ground and the bending carried out in a vertical plane, as above mentioned.

What I claim as my invention and desire to secure by Letters Patent is:

1. In a tube bending machine having a radial sweep arm carrying a grooved member bearing on the tube, a bent up sheet metal former comprising in cross section a semi-circular part and resilient side flanges projecting to the overall diameter of the largest tube which can be fitted into the former, the flanges being splayed slightly so that the groove in the former, for the reception of the pipe being bent, tapers outwardly to receive diametrically different size tubes.

2. In a pipe bending machine having a radial sweep arm carrying a grooved member bearing on the pipe, a former consisting of a strip of sheet

- metal bent transversely to a semi-circular form with projecting resilient side flanges and curved round longitudinally to the necessary radius, a tube welded to one end of the grooved strip and forming a support for the bending machine during use, and a second tube welded transversely to the first-mentioned tube and to the other end of the strip and forming a socket for the pivot about which the sweep arm swings.
- 10 3. In a tube bending machine having a radial sweep arm capable of being swung round a grooved former to bend the tube, a grooved shield having a cylindrical concave face of slightly greater curvature at its centre than towards its edges, said shield being slideable on said arm until the rear edges of the shield enter the groove in the former.
- 15 4. A tube bending machine comprising a bent up sheet metal grooved former, supporting members welded thereto, a radial bending lever pivoted on one of said members and capable of swinging about said former, an abutment adjacent one end of the former, and a grooved shield slideable on the bending lever until one end of the shield enters the groove in the former, said shield having a concave face of slightly greater curvature at the centre than towards its edges.
- 20 5. A tube bending machine having a plurality of grooved sheet metal formers of different sizes, supporting means for said formers, a bending lever pivoted on said supporting means and capable of a swinging movement in relation to said formers, straight grooved members slidably adjustable on said lever, one member being associated with each former, means for securing said members in adjusted tube bending position with

their rear edges only in the grooves of the formers, and abutments for holding the end of a tube being bent.

6. A pipe bending machine comprising sheet metal formers, a supporting tube welded to said formers, an additional tube welded to said formers transversely of the first mentioned tube, a radial bending lever pivoted on said additional tube, grooved shields slideable on said lever and movable round the formers by swinging movement of said lever, means for securing the shields in position on the lever, an arm secured on the first-mentioned tube and carrying abutments for the end of the pipe to be bent, and a supporting leg insertable into either of the tubes.

15 7. A pipe bending machine comprising sheet metal formers, a supporting member secured to said formers, an additional supporting member connected to said formers transversely of the first mentioned supporting member, a radial bending lever pivoted on said additional supporting member, grooved shields on said lever and movable round the former by swinging movement of said lever, means for securing the shields in position on the lever, an arm secured on the first mentioned supporting member and a stop carried by said arm to engage the end of the pipe to be bent.

20 8. For use in a tube bending machine having a radial sweep arm carrying a grooved member bearing on a tube, a former constructed with a groove having resilient outer walls to support the tube, the said resilient walls of the groove permitting the insertion of diametrically different size tubes.

25 JOHN HENRY HAWES.
